UNITED STATES PATENT OFFICE.

NEIL D. MUNN, OF DRESDEN, ONTARIO, CANADA.

STARTER FOR AUTOMOBILE-MOTORS.

1,333,817.

Specification of Letters Patent. Patented Mar. 16, 1920.

Application filed April 9, 1919. Serial No. 288,835.

To all whom it may concern:

Be it known that I, NEIL D. MUNN, of Dresden, in the county of Kent, Province of Ontario, Canada, have invented certain new and useful Improvements in Starters for Automobile-Motors, of which the following is a specification.

This invention relates to starters of the mechanical type operable from a point within 10 in the vehicle. With such starters it has so far been difficult to get satisfactory results when a motor is cold or otherwise hard to start, as the movement of the revolution of the engine shaft obtainable has not exceeded 15 from one quarter to one half a revolution, and my object is to devise a mechanical movement which will fit into the limited space available and which will give substantially one complete revolution to the engine 20 shaft.

I attain my object by means of the constructions hereinafter described and illustrated in the accompanying drawings in which—

25 Fig. 1 is a front elevation of my improved starter partly broken away;

Fig. 2 a side elevation of the same, partly in section and partly broken away;

Fig. 3 a horizontal section of the same on 30 a larger scale;

Fig. 4 a section of the clutch which permits the engine shaft to run ahead of the starter;

Fig. 5 a side elevation of part of a motor 35 car showing the preferred location of the starting crank; and

Fig. 6 a plan view of the same.

In the drawings like numerals of reference indicate corresponding parts in the different figures.

1 is the engine shaft of the motor of an automobile. On the end of this shaft is fitted a sleeve 2, the outer end of which is notched for engagement with the starting 45 crank. The usual fan belt pulley 3 is secured to the sleeve by means of the pin 4, which passes through the pulley, sleeve and engine shaft. On the sleeve is also loosely fitted the spur gear 5, and means are provided whereby the gear is given a driving 50 engagement with the sleeve 2 to turn over the engine shaft, while the engine shaft is free to run ahead of the pinion. The preferred arrangement is shown particularly 55 in Figs. 4 and 6. The sleeve 2 has wedge

shaped notches 6 formed in part of its periphery in which are set balls or rollers 7. At the bottoms of the notches there is just sufficient room for the rollers, while as the rollers ride up the inclined faces of the 60 notches they are jammed against the inner periphery of the spur gear 5.

Pivotedly mounted on the outer end of the sleeve 2 is a rock arm 8 held in place by the collar 9. This arm has a pinion 10 journaled thereon meshing with the spur gear 5. 65 11 is an internal gear provided with lugs 12 whereby it may be secured to the engine bed concentric with the engine shaft, and proportioned to mesh with the pinion 10. It is 70 not necessary that this gear extend through a full circle, something less than 180 degrees being sufficient for my purpose.

It is evident that by rocking the arm 8 the spur gear will be rotated and that owing to the proportion of the gearing, the pinion will be given a complete rotation while the arm 8 moves through an arc of something less than 180 degrees.

It is important in the case of a back fire 80 that the gearing should be out of mesh when the arm is in its initial position. The teeth of the internal gear are therefore omitted from that part of the gear adjacent the pinion 10 when the arm 8 is in its initial position. The pinion is then free to rotate, if reverse motion has been given to the gear 5 by back firing of the motor, without the arm 8 being affected.

To give effective leverage at the beginning of the operative movement of the rock arm, I pivot on the end of the arm the link 13, and provide a stop 14 on the arm which limits the swinging movement of the link in the direction of the shaft when the arm is in its initial position as shown in Fig. 1. This link pulls out more or less into alignment with the rock arm as the rock arm reaches its limit of movement in the other direction, as shown in dotted lines in Fig. 1.

100 Any suitable means may be provided to rock the arm 8. In the drawings I show a chain 15 connected to the link 13 and adapted to be wound on a drum 16 on the operating shaft 17 suitably journaled beside the motor and extending rearwardly through the dash of the car to a position convenient to the steering wheel.

105 The operating shaft is actuated by means of bevel gearing 18 from the crank 19, the 110

operating shaft, gearing and crank being suitably supported on the bracket 20 clamped to the steering post 21.

It will be necessary to provide means to prevent a backfire of the motor from violently rotating the crank 19 in a reverse direction and possibly injuring the operator. I therefore provide a frictional driving connection between the drum 16 and the operating shaft 17 adapted to release under the influence of momentum. A simple arrangement is shown particularly in Figs. 1 and 2 of the drawings. A collar 22 is secured to the operating shaft against which one end 15 of the drum 16 bears. A coarse thread is formed on the operating shaft at the other side of the drum on which is screwed a nut 23 having a weight 24 secured thereto. When the operating shaft is rotated in the proper direction to rotate the drum 16 to start the engine, the nut 23 screws tightly against the drum and the gear is given a driving connection with the operating shaft. However, if the operating shaft or drum is suddenly stopped, as would be the case if the motor back-fired, the momentum of the weight 24 would continue the rotation of the nut 23 and unscrew it sufficiently to release the drum. When conditions become normal, 30 the drum is readily re-engaged with the operating shaft by suitably rotating the latter. The arm 8 is normally held in its initial position by the coil spring 22 secured at one end to the arm and at the other end to a 35 stationary part.

What I claim as my invention is:—

1. In a mechanical starter for motors, the combination with the shaft to be rotated of a spur gear; clutch mechanism forming a 40 driving connection between the spur gear and the shaft adapted to permit of the shaft running free of the gear; an arm journaled concentric with the shaft; a pinion journaled on the arm meshing with the gear wheel; 45 and a stationary internal gear with which the pinion also meshes.

2. A mechanical starter constructed as set forth in claim 1 in which, to prevent damage in case of back firing of the motor, the

internal gear is so proportioned that the 50 pinion disengages therefrom when the arm is in its initial position.

3. A mechanical starter constructed substantially as set forth in claim 1 having a link for the connection of operating means 55 pivoted on one end, means being provided limiting the swing of said link toward the shaft, when the arm is in its initial position.

4. In a mechanical starter for motors, the 60 combination with the shaft to be rotated of a rotatable part; clutch mechanism forming a driving connection between the rotatable part and the shaft adapted to permit of the shaft running free of said part; and means 65 for imparting a turning movement to said rotatable part including an operating shaft, a rotatable part rotatably mounted on said operating shaft, a clutch normally giving the operating shaft a driving connection 70 with the rotatable part, and momentum operated release means adapted to disengage the clutch on a sudden stoppage of the turning movement of the operating shaft.

5. In a mechanical starter for motors, 75 the combination with the shaft to be rotated of a rotatable part concentric therewith; clutch mechanism forming a driving connection between the rotatable part and the shaft adapted to permit of the shaft running free of said part comprising a part 80 rotating with the shaft having peripheral cam notches formed therein and rollers located in said cam notches adapted to frictionally engage the inner periphery of the first mentioned rotatable part; and means for imparting a turning movement to said rotatable part including an operating shaft, a rotatable part rotatably mounted on said operating shaft, a clutch normally giving 90 the operating shaft a driving connection with the rotatable part, and momentum operating release means adapted to disengage the clutch on a sudden stoppage of the turning movement of the operating shaft. 95

Signed at Toronto, Canada, this 27th day of March, 1919.

NEIL D. MUNN.
